B. O. W. HESSELMAN AND O. G. M. MATTSSON,
MACHINE FOR PRODUCING HOLLOW BRICKS.
APPLICATION FILED APR. 10, 1915.

1,386,404.

Patented Aug. 2, 1921.

UNITED STATES PATENT OFFICE.

BROR OSCAR WALTER HESSELMAN AND OSKAR GOTTFRID MEINHARD MATTSSON, OF STOCKHOLM, SWEDEN.

MACHINE FOR PRODUCING HOLLOW BRICKS.

1,386,404.

Specification of Letters Patent.

Patented Aug. 2, 1921.

Application filed April 10, 1915. Serial No. 20,513.

(GRANTED UNDER THE PROVISIONS OF THE ACT OF MARCH 3, 1921, 41 STAT. L., 1313.)

To all whom it may concern:

Be it known that we, BROR OSCAR WALTER HESSELMAN and OSKAR GOTTFRID MEINHARD MATTSSON, of Stockholm, Sweden, subjects of the King of Sweden, have invented certain new and useful Improvements in Machines for Producing Hollow Bricks, (in which we have filed applications in Sweden the 16th June, 1914; in Hungary the 29th April, 1914; in Portugal the 25th May, 1914; in Russia the 22nd April, 1914, (Russian style;) in Finland the 27th April, 1914; in Norway the 25th April, 1914; in Denmark the 11th April, 1914; in Belgium the 5th May, 1914; in Switzerland the 16th June, 1914; in Holland the 29th June, 1914; in France the 4th May, 1914; all filed by Aktiebolaget Lean, Stockholm, with our knowledge and consent,) of which the following is a specification.

20 In producing hollow bricks in molds movable in one direction and provided with cores movable in the opposite direction it is important that this movement is absolutely exact so that no displacement of the molds or 25 of the cores tending to destroy the bricks produced, can arise. The present invention relates to a machine in which the molds and the cores have a very precise movement relatively to one another, being supported by 30 two plates or holders connected to one another at the ends by double levers.

The invention is illustrated in the accompanying drawing, in which Figure 1 is a side view and Fig. 2 an end view of the 35 machine. Fig. 3 shows a detail.

The machine consists of a table or the like 1, supported by suitable tubular uprights 6. Over the top of the table a holder or plate 3 for the outer molds 7 is provided, the inner molds or the cores 4 being attached 40 to another holder or plate 2 under the table. The table is provided with openings for the cores so that the same can pass into the outer molds 7. The plate 2 is provided with eyes 45 or sleeves surrounding the tubular uprights and being guided by the same, the plate 3 being provided with bars 5, movable in the said uprights. The upper plate 3 supporting the outer molds 7 is provided with openings 8, corresponding to the inner cross section of the outer molds, these openings serving to make it possible to insert the material 50 into the molds and for its packing in the same. At each end of the frame double levers 10 are provided, being pivotally attached 55 to the plates 2 and 3 respectively and stub shaft 37. The levers 10 are by means of links 14, 15, connected with a common shaft 13 operated by means of a lever 16. For facilitating the manipulation of the lever 16 60 and beginning the movement, a treadle 25 is loosely mounted on the shaft 13 and rests with a dog 26 against the lever 16. By pressing down the treadle the dog 26 will, with the aid of the lever 16 rotate the shaft 65 13, whereby the movement begins and the lever 16 is brought in such position that it can be readily gripped by the machine attendant.

For packing the materials in the molds a 70 system or pistons 17 is used, this system being supported by a lever 18, attached to a rotatable upright shaft or bar 35. The shaft 35 passes through a hollow sleeve or bearing 36 on the plate 3 and is provided with a 75 notch, in which engages a lever 22 arranged on the stand and pivoted to the link 33 and at the one end influenced by a weight 21. The lever 22 is held by the weight 21 in such a position that it tends to hold the shaft 35 80 elevated, so that the pistons do not reach the table 3, when they are brought to or from their position. Midway between the pistons the lever 18 is provided with a recess for a wooden plug 19, on which it is possible to 85 strike with a hammer, thereby pressing the pistons in the molds. The lever 22 is at its front end connected with a treadle 24 by means of a link 23, the weight 21 being lifted up by pressing down this treadle. The lever 90 22 is provided with a pivoted hook 27, adapted to engage a pin 28 attached to the table 1, so that when the lever 22 is pressed down by means of the treadle 24, it is held in the depressed position. As the lever 22 influences the upright shaft 35, this shaft and the pistons 17 will therefore also be held depressed, until the hook 27 is released from engagement with the pin 28. This is accomplished by means of a lever 31, attached to 95 the movable plate 3 and provided at one end with a hook, this lever engaging a shoulder 30 on the hook 27 and moving the hook out of engagement with the pin 28 when the table 3 is lifted up. By this arrangement 100 105 the pressure on the bricks will always cease

at the same moment just before the molds quite leave the stones.

The machine operates in the following manner. Both plates are brought in to the position shown on the drawing by means of the handle 16 but previously plates with openings for the cores are put on the table 1 under the outer mold 7, so as to form bottoms for the molds. The piston system is already brought away from the machine. Then the molds are filled with the material to be used, which material is packed in the molds in a suitable manner. The piston system is then brought into position over the openings in the table or plate 3. By striking on the plug 19 and at the same time pressing down the treadle 24, the pistons 17 will be brought down on to the filling in the mold 7 and held there in the manner described. Then the treadle 25 is pressed down and the handle 16 is turned so that it can be caught by the attendant and operated so that the plate 3 will be raised and the plate 2 will be lowered. By the lifting of plate 3 the hook 27 will be released from engagement with the pin 28, whereby the pressure against the bricks ceases. The completed bricks remain on the plates and can be removed, and then the same process is repeated.

Having now particularly described and ascertained the nature of our said invention and in what manner the same is to be performed, we declare that what we claim is:—

1. In a machine for molding blocks, the combination of a mold, a support, means for moving the said mold into operative position at one side of the support and into inoperative position away from the support, means for applying pressure to the material in the mold and means for automatically relieving the pressure when the mold reaches its inoperative position.

2. In a machine for molding blocks, the combination of inner and outer mold-parts, a support, means for moving the mold-parts toward each other into operative position at one side of the table and away from each other into inoperative position, means for applying pressure to the material in the mold and means for automatically relieving said pressure when the mold-parts reach their inoperative position.

3. In a machine for molding blocks, the combination of a mold, a support, means for moving said mold into operative position at one side of the support and into inoperative position away from the support, means for applying pressure to the material in the mold and means connected with said means for moving the mold for relieving the pressure when the mold-parts reach their inoperative position.

4. In a machine for molding blocks, the combination of a mold, a support, means for moving the said mold into operative position

at one side of the support and into inoperative position away from the support, means for applying pressure to the material in the mold, means for locking said last-mentioned means in working position and means for automatically releasing the lock when the mold reaches its inoperative position.

5. In a machine for molding blocks, the combination of inner and outer mold-parts, a support, means for moving the mold-parts toward each other into operative position at one side of the support and away from each other into inoperative position, means for applying pressure to the material in the mold, means for locking said last-mentioned means in working position and means connected with said means for moving the mold for releasing the lock when the mold-parts reach their inoperative position.

6. In a machine for molding hollow blocks, the combination of a table, uprights supporting said table, inner and outer mold-parts slidably carried by said uprights, toggle-levers to which said mold-parts are pivotally connected for movement into and out of operating position, and means for operating said toggle-levers.

7. In a machine for molding hollow blocks, the combination of a table, tubular uprights supporting said table, a plate, an inner mold-part attached to said plate, a second plate having legs movable in said tubular uprights, an outer mold-part attached to said second plate, toggle-levers to which said plates are pivotally attached, an operating shaft, and links connecting said toggle-levers to said operating shaft.

8. In a machine for molding hollow blocks, the combination of a table, tubular uprights supporting said table, a plate, an inner mold-part attached to said plate, a second plate having legs movable within said tubular uprights, an outer mold-part attached to said second plate, toggle-levers to which said plates are pivotally connected, and means for operating said toggle-levers to move said mold-parts into and out of operating position.

9. In a machine for molding hollow blocks, the combination of a table, tubular uprights supporting said table, a plate slidably carried by said tubular uprights, an inner mold-part attached to said plate, a second plate provided with legs movable in said tubular uprights, an outer mold-part attached to said second plate, toggle-levers to which said plates are pivotally connected, and means for operating said toggle levers to move said mold-parts into and out of operating position.

10. In a machine for molding hollow blocks, the combination of a table, tubular uprights supporting said table, a plate, an inner mold-part attached to said plate, a second plate having legs movable within said

tubular uprights, an outer mold-part attached to said second plate, toggle-levers to which said plates are pivotally attached for movement of said mold-parts into and out 5 of operating position, a shaft for operating said toggle-levers, links connecting said shaft and said toggle-levers, an operating lever for said shaft, and a treadle attached to said shaft for facilitating the operation 10 of said lever.

11. In a machine for molding hollow blocks, the combination of a table, tubular uprights supporting said table, a plate, an inner mold-part attached to said plate, 15 sleeves slidably carried by said tubular uprights and attached to said plate, a second plate having legs movable within said tubular uprights, an outer mold-part attached to said second plate, and means for moving said 20 mold-parts into and out of operating position.

12. In a machine for molding hollow blocks, the combination of inner and outer 25 assemblable mold-parts, means for moving the mold-parts into operative and inoperative positions, a plunger for applying pressure to the molded block while the mold is assembled, a shaft, a lever connecting said shaft and said plunger, means for normally 30 maintaining said plunger in inoperative position, means for maintaining said plunger in its operative position while said mold-parts are assembled and means for automatically returning the plunger to its in- 35 operative position when the mold-parts reach their inoperative position.

13. In a machine for molding hollow blocks, the combination of inner and outer assemblable mold-parts, a plunger for applying pressure to the molded block while the 40 mold is assembled, a shaft, a lever connecting said shaft and said plunger, a notch in said shaft, a lever engaging said notch, a weight on one end of said lever normally maintaining said plunger in inoperative position, and means for maintaining said plunger in its operative position while said mold-parts are assembled. 45

14. In a machine for molding hollow blocks, the combination of inner and outer 50 assemblable mold-parts, a plunger for applying pressure to the molded block while the mold is assembled, means tending to maintain said plunger in its inoperative position, a shaft, a lever connecting said shaft and 55 said plunger, means for moving said plunger into operative position, a second lever engaging said shaft, a hook pivoted to said second lever, a pin movable with said inner mold-part and engaging said hook to maintain 60 said plunger in its operative position, and a lever movable with the outer mold-part and adapted to release said hook from said pin.

In testimony whereof we have signed our names to this specification in the presence 65 of two subscribing witnesses.

BROR OSCAR WALTER HESSELMAN.
OSKAR GOTTFRID MEINHARD MATTSSON.
